UNITED STATES PATENT OFFICE

2,513,559

RUG AND METHOD OF MAKING SAME

Benjamin A. Greenberg, Chicago, Ill., assignor
to Charm Tred Mills, Incorporated, Chicago,
Ill., a corporation of Illinois.

Application December 13, 1946, Serial No. 716,042

8 Claims. (Cl. 2—278)

1

This invention pertains to articles of manufacture such as decorative and utilitarian coverings and protective articles such, for example, as rugs, mats, toilet seat covers, bedspreads, draperies, and similar articles, including a base fabric covered on one side with a continuous or a substantially overall nap or pile which forms an attractive foundation or background for decorative configurations or designs superimposed upon the pile to produce an embossed-like decorative effect by means of an improved fringe or tape secured in place over the pile-forming face of the rug or article being formed.

The improved rug or article includes a base fabric, of one or more plies, covered entirely or substantially so with a pile and with border-forming tufts or fibers of yarn or the like stitched to the margins of the base fabric. The pile thus formed may be continuous or of uniform design, such as a waffle pattern, and the present invention relates primarily to the use of an improved type of double fringe or tape adapted to have parts thereof cut and unraveled at a predetermined time so that when the improved fringe or tape is stitched upon the pile covering along predetermined paths a ball or pompon-like design is produced, to project above the rug pile and appearing as though each of the balls or pompons were individually affixed instead of being produced by the improved fringe or tape.

The present invention is more particularly directed to an improved type of rug or similar article embodying a base fabric covered by a pile of selected form and design, upon which an improved ball or pompon-forming fringe or tape is adapted to be stitched along prescribed paths or lines through the pile and to the foundation fabric to eventually produce a rug or other article with a pile covering dominated by the superimposed design of spaced balls or pompons, producing a novel effect and obviating the independent application of the balls or pompons, by the method heretofore commonly practiced and requiring tedious and concentrated work, excessive time, and thereby materially increasing the cost of the article.

It is an object of the present invention to provide an improved rug or similar article and a method of making the same which is economical, practical and efficient.

It is also an object of this invention to provide an improved type of rug or similar article wherein a foundation fabric is covered with a pile to form a background for a superimposed design effected by means of an improved ball or pompon-forming fringe or tape adapted to be partly

cut, then secured directly over the pile and to the foundation fabric and then partially unraveled to produce a spaced ball design upon the pile background.

It is a further object of this invention to provide an improved double type of yarn fringe or tape including removable substantially parallel stitched chains connecting transverse yarn groups which are also connected by means of integral yarn links whereby the fringe or tape may be secured to a pile-like background or foundation to hide the connecting links in the pile and produce a superimposed design or spaced balls or pompons when the stitched chains have been removed.

Still another object of the invention is the production of a ball design forming fringe or tape, including link connected transverse yarn loops temporarily connected to one another by a plurality of removable stitchings along opposite longitudinal margins of the fringe or tape, whereby spaced ball-like designs may be quickly and conveniently superimposed upon pile covered foundations to produce rugs or the like of attractive and effective appearance having a pile-on-pile effect.

Still another object of the invention is to provide an improved type of ball or pompon-forming tape or fringe readily applicable for producing spaced ball-like designs upon a base fabric as well as over pile-covered foundations.

It is an important object of this invention to provide a ball-producing fringe or tape having inner and outer stitchings on opposite margins thereof to temporarily hold link-connected groups of yarn loops in place before the loops are transversely cut to the outside of the inner stitchings while the inner portions of the loop groups are permitted to remain connected until the loop groups and the connecting links thereof are permanently secured to a fabric foundation or the like, after which the inner stitchings are removed to produce spaced balls or pompons forming an embossed-like design on the foundation fabric consisting of either a plain or a pile-covered material.

Other and further important objects and features of this invention will be apparent from the disclosures in the specification and the accompanying drawings.

The invention, in a preferred form, is illustrated in the drawings and hereinafter more fully described.

On the drawings:

Figure 1 is a fragmentary top plan view of a ball or pompon-producing tape or fringe embody-

ing the principles of this invention, illustrated in association with a double-cutter mechanism adapted for cutting transversely through the outer portions of loop groups of yarn for removing the bight portions of the loops, together with the outer retaining stitchings, to prepare the fringe prior to the stitching of the same longitudinally along a center line upon a pile covered or plain base fabric for producing a superimposed ball or pompon-like design on the article being made.

Figure 2 is a fragmentary plan view of a section of a pile covered foundation with a portion of the pile removed to show the base fabric to more clearly disclose a portion of the cut fringe stitched thereto, showing the opposite sides of the fringe moved upwardly toward one another by the fastening stitches and also illustrating the inner stitchings partly unraveled to release the cut strands to permit the cut strands from opposite sides of each group to move toward one another or cluster to form ball-like puffs or pompons in spaced relation to one another along predetermined paths to form a selected design superimposed upon the pile foundation of the article being produced.

Figure 3 is a fragmentary top plan view of a corner portion of a rug or article produced by means of the improved ball-forming fringe stitched upon the pile of a foundation fabric and within a border portion to produce an improved type of rug or article wherein a ball or pompon design is produced to project above the pile of the rug or article.

Figure 4 is a fragmentary sectional view taken substantially along the line IV—IV of Figure 2 through the rug pile to one side of one of the balls or pompons and also diametrically through another of the balls or pompons to more clearly illustrate the construction of the improved rug or article.

Figure 5 is a fragmentary bottom plan view of a rug showing the foundation fabric and illustrating the stitching for producing the pile on the opposite side of the rug, the border-producing stitches and also the path of the stitches for securing the ball or pompon-producing design superimposed upon the pile on the upper side of the rug.

As shown on the drawings:

This invention relates to pile type articles of manufacture such as rugs, bath mats, toilet seat covers, draperies, bedspreads and other articles adapted to be produced on a foundation fabric uniformly covered with a pile or weft to form a soft background upon which is superimposed a selected design formed of yarn balls or pompons resulting from the use of an improved type of ball forming fringe or tape stitched or secured along predetermined lines upon the pile background or foundation of the article produced.

An important feature of the invention is the provision of an improved double-edge type of fringe, preferably machine manufactured out of string or yarn, which is looped transversely with the looped groups forming sections which are integrally connected by chain-like links of the yarn or string along a center line of the fringe between opposite rows of removable chain stitchings or the like.

Referring to Figure 1, the yarn or string, out of which the fringe or tape is made, is transversely looped to provide groups of loops 1 which project back and forth beyond a longitudinal center line of the fringe and terminate at the transverse cen-

ter line in groups of strands which are waved to form longitudinal connecting links 2 between the loop groups.

As the loop groups and the connecting links are formed they are permanently held assembled by means of spaced longitudinal central stitchings 3. Simultaneously with the forming of the loop groups, the connecting links and the center line stitching, the outer portions of the yarn loops 1 are traversed by substantially parallel removable inner chain-stitches 4 and outer chain-stitches 5. While the inner and outer chain-stitches are preferably formed by single thread chain-stitching, it is to be understood that other removable temporary types of inner and outer stitchings may be used.

As clearly illustrated in Figure 1, the outer and inner chain-stitches 5 and 4, respectively, form connections between the spaced groups of yarn loops, said connections being disposed on opposite sides of the fringe links 2. It will thus be noted that the improved fringe or tape, which is the primary medium essential for the production of a uniformly spaced ball or pompon decoration upon the weft or pile of a rug or other article of manufacture, is preferably made of transversely looped strands of yarn arranged in spaced groups connected by integral zig-zag or wavy yarn links, with the bight portions of the loops transversely stitched longitudinally of the fringe and on both sides of the longitudinal center line of said fringe by means of selectively removable inner and outer chain-stitch seams, portions of which also act as temporary connecting means between the groups of yarn loops.

One of the main features of the invention is the provision of an improved method for producing an article such as a rug in which a base fabric is first covered by an overall or continuous weft or pile to form a background or foundation for embossed or raised decorations to be superimposed thereon, in the form of equidistantly spaced balls or pompons adapted to be produced by an improved fringe or tape, the securing of which along predetermined lines determines the design effect produced on the pile background or base. The embossed ball-like superposed designs may or may not be surrounded by a rug border or cut tuft edge to form a covering and a finish for the edges of the rug base fabric and the margins of the pile covering the same.

After the double type ball or pompon forming fringe or tape has been produced, with the yarn loop groups and the integral connecting links fastened together by means of the central stitching seams 3, and by the removable chain-stitched seams 4 and 5 the improved fringe or tape is ready for a cutting treatment to prepare the fringe so that it may be permanently superimposed upon a plain or pile-covered foundation. After the cutting treatment the fringe is secured along a selective decorative configuration over the pile or weft of an article such as a rug formed of chenille or other selected material to produce a projecting ball design superimposed on a continuous or overall chenille pile or on a waffle-type chenille covering applied to a fabric backing to produce a finished product such as illustrated in Figure 3.

To condition the ball-forming fringe for the making of a rug or other pile covered article, the fringe is fed into a cutter mechanism of a selected standard type, illustrated in Figure 1 and including a driven shaft 6 having cutter disks 7 mounted thereon in spaced parallel relation so

that when the fringe is fed through the cutter mechanism the cutter disks 7 will cut transversely across the outer portions of the yarn loops 4 closely adjacent the inner side of the outer seams 5, to thereby sever or cut off the bight portions 8 of the loops 4 along the cut edges 9, as illustrated in Figure 1, to form cut strands projecting from opposite margins of the cut fringe to subsequently serve as a means for producing equidistantly spaced strand clusters as hereinafter more fully described.

The cut fringe, in the form illustrated in the lower portion of Figure 1 beneath the shaft 6, is now ready to be applied by stitching to a rug foundation, while the connecting chain-stitch seams 5 with the cut-off bight portions 8 still attached thereto are discarded as waste material. These chain-stitch seams 5 act to hold the bight portions 8 attached thereto, thereby preventing the same from scattering and flying around in the factory to make a mess.

To form an article of manufacture such as a rug, with an upwardly projecting decorative design of spaced balls or pompons over a pile background, a base fabric or backing sheet 10 of one or more plies of canvas or the like is cut to a desired shape and size, such as the rectangular-shaped rug illustrated fragmentarily in Figure 5. The base fabric 10 may be of a selected grade of canvas, duck, or other strong suitable foundation material upon which the pile or weft-forming tape is secured along the lines of stitching 11 to substantially uniformly cover one face of the base fabric 10 with strands or tufts 12. The strands or tufts 12 may be produced by any standard method to provide a pile covering on the base fabric, and said pile covering may be formed of chenille, wool yarn, or any other suitable material, either as a continuous pile covering or, if preferred, a waffle-like pile covering such as illustrated in Figures 2 and 3.

The edges or margins of the base fabric and the pile covering may be covered or finished by means of a tufted border or edging 13 in which the strands may be of the same length as the strands forming the rug pile, or the border-forming tuft strands may be longer than the pile-forming strands to form a raised finishing border for the rug.

It is to be understood that any suitable type of pile covering and border may be produced on the rug base fabric to provide a suitable background for setting off an embossed or upwardly projecting design upon the pile background by means of the improved ball or pompon-forming fringe or tape of the type illustrated in Figure 1.

As clearly illustrated in Figure 5, the rug border 13 is produced by two or more rows of parallel stitching 14.

To produce the ball or pompon design upon the pile background the cut tape superimposed upon the pile background of the rug is secured along a path of selected configuration by means of a longitudinal center stitching 15, as shown in Figure 2. The fringe attaching stitching 15 applied between the permanent longitudinal central stitchings 3 of the fringe not only traverses the groups of yarn loops or strands but also crosses the waved or zig-zag links 2 of the fringe. The ball-forming fringe, when thus secured in place over the pile of the rug, securely holds the yarn groups in spaced connected relation with the waved links 2 substantially buried between the strands or tufts of the rug pile 12, so that in the

finished rug so produced the connecting links are not normally visible.

As clearly illustrated in Figure 2, the cut ball-forming fringe having the inner chain-stitchings 4 still in place serves to hold the cut strands of each yarn group in place while the fringe is being stitched over the pile and to the base fabric of the rug. The fringe securing stitching 15 is applied in such manner that a desired design of the ball decoration is produced. In the present showing the stitching 15 as illustrated in Figure 5 is applied in transversely and longitudinally crossing lines, while shorter portions of the ball-forming fringe are applied with diagonally crossing lines of stitching 15 in substantially the middle portions of the squares formed by the transverse and longitudinal lines of stitching 15.

The ball-forming fringe thus applied to the pile covered rug will accordingly produce an embossed or pompon-like design upon the pile background as illustrated in Figure 3 in such a manner that the links 2 of the fringe are substantially hidden in the tufts of the pile. After the ball-forming fringe has been stitched in place as above described to follow a prescribed line of design, the next step in the method of producing the finished product is to have an operator unravel the inner chain-stitchings 4, thereby releasing the cut strands of each group. The released strand halves on opposite sides of the stitching 15 are thus permitted to move upwardly toward one another to form equidistantly spaced yarn clusters to produce the upwardly projecting decorative balls or pompons 16, the lower supporting ends of which are buried in the strands of the rug pile 12, to produce a decorative ball or pompon design upon the rug pile and giving the impression that the balls or pompons are individually applied on the pile background and within the border 13 of the rug.

After the tuft or ball-forming fringe is stitched or secured to the foundation fabric 10 and over the pile 12, along desired paths to produce a selected design or motif of the balls or pompons 16 upon the pile background, and after the removal of the inner chain-stitchings 4, the rug or other article being produced is ready for the final step in the method. The final step consists of subjecting the pile rug with the decorative pompons 16 thereon to the action of steam to soften and fluff the yarn strands forming the pile 12 as well as the cut strands forming the balls or pompons 16 to produce the desired soft, fluffy pile covering with the ball design projecting upwardly therefrom.

The improved method of producing a rug or other pile-like article briefly consists of covering a base fabric with a pile covering and with a tufted border, if desired, then cutting transversely through groups of yarn loops of the fringes to remove the loop bights together with the outer stitchings. The cut fringe is then permanently stitched along a predetermined path over the pile foundation of the rug prior to unraveling the inner stitchings to permit the strand portions on opposite sides of the securing stitching to move upwardly toward one another to form balls or pompons upon the pile background of the rug, and completing the article by subjecting the rug thus produced to a steaming treatment to fluff the rug pile and the embossed design-forming balls or pompons.

In the formation of rugs or other articles of the type referred to, the rug pile, the border and the embossed pompon design superimposed on

the pile may all be of the same color, or the colors of the various portions of the rug may be of different selected color combinations to produce the effects desired.

In accordance with the foregoing description it will be noted that an improved type of rug or similar article of manufacture may be quickly and inexpensively produced by means of an improved ball or pompon-forming fringe of a type which may readily be applied over the pile of an article to produce a finished product with a pile background having a decorative design projecting upwardly from the pile, which design is formed by equidistantly spaced balls or pompons adapted to be applied in grouped relationship but giving the appearance of being individually affixed.

While a ball design-forming fringe for use on pile rugs has been described to include the preliminary step of severing the bight portions of the fringe loop groups before the fringe is secured upon the pile or base fabric of a rug to cause the formation of balls or pompons upon release of the inner stitchings of the fringe to produce designs of balls or pompons upon the rug pile, it is to be understood that the improved ball-forming fringe may be constructed to provide decorative balls formed of uncut loops. An improved fringe for the purpose of forming loop balls as described may omit the outer stitchings and the cutting operation on the loop groups. With a fringe of this type the fringe may be stitched along a center line upon the pile of a rug base fabric to bury the fringe links in the rug pile and permitting the opposite portions of the stitched loop groups to move upwardly toward one another. The single chain-stitchings on each of the longitudinal margins of the fringe may then be unraveled or removed to permit the released loops to intermingle, to form decorative balls or pompons to project upwardly from the pile of the rug.

It will of course be understood that various details of construction or changes in the steps of the method of producing a rug or the like may be varied through a wide range without departing from the principles of this invention, and it is therefore not the purpose to limit the patent granted hereon otherwise than necessitated by the scope of the appended claims.

I claim as my invention:

1. A pompon-forming fringe comprising a fringe body consisting of yarn looped back and forth transversely of the body to form spaced groups of yarn loops with portions of the yarn diverted from opposite sides of each group to form narrow connecting yarn links joining the loop groups along the longitudinal center line of the fringe, central longitudinal stitching crossing the loop groups and the strands of the narrow yarn links to hold the loop groups and the links in position, inner stitches removably secured only across the yarn loops of said loop groups on opposite sides of the links and spaced therefrom to temporarily hold the yarn loops in place, and outer stitches also removably secured only across the yarn loops of the loop groups on opposite sides of the links and spaced therefrom to the outside of the inner stitches to temporarily hold the loop groups connected in spaced relationship.

2. In an article of manufacture, a pompon-forming fringe comprising alternately arranged groups of oppositely projecting yarn loops and integral yarn connecting links permanently held together by longitudinal central stitchings, and a plurality of completely removable means spaced

from the connecting links and forming temporary inner and outer stitches crossing both longitudinal margins of the loop groups.

3. A ball forming fringe for decorating articles of manufacture such as rugs, draperies and the like, said fringe comprising a body constructed of alternating groups of oppositely directed yarn loops and yarn links integrally connecting said groups, a central seam stitched across the loop groups and longitudinally of said links to permanently hold the same in position with respect to one another, inner chain-stitch seams spaced from the links on opposite sides of the central seam and removably stitched only across the loop groups and forming inner temporary connecting chains between said loop groups, and outer chain-stitch seams spaced from the links and also removably stitched only across the loop groups and forming outer temporary connecting chains between the loop groups.

4. A ball or pompon-forming decorative fringe comprising a body constructed of alternating groups of yarn loops and yarn links forming a continuous yarn structure, a central seam stitched across the loop groups and longitudinally of the links to permanently hold the same in position with respect to one another, and inner and outer chain-stitch seams spaced from opposite sides of the links on opposite sides of the central seam and removably stitched only across the yarn loops and providing temporary connecting chains between said loop groups, said outer chain-stitch seams removable prior to the use of the fringe by cutting off the bight portions of the yarn loops and discarding the outer chain-stitch seams with the cut off bight portions still attached thereto.

5. A ball or pompon-forming decorative fringe comprising a body constructed of alternating transverse yarn loop groups and integral longitudinal yarn connecting links, a central seam stitched across the loop groups and longitudinally of the links to permanently hold the loop groups and the connecting links in position with respect to one another, and inner and outer chain-stitch seams spaced from opposite sides of the links and on opposite sides of the central seam and removably stitched across the outer portions of the loop groups only and forming temporary connecting chains spaced from the links and connecting said loop groups, said outer chain-stitch seams removable prior to the use of the fringe by cutting off the bight portions of the loops and discarding the outer chain-stitch seams with said cut off bight portions still attached thereto, said inner chain-stitch seams removable by unraveling after the cut fringe has been secured in place upon a supporting fabric to form links connected by decorative balls or pompons thereon out of the cut and released strands of the loop groups.

6. A fringe comprising a body constructed of alternating transverse yarn loop groups and longitudinally disposed sinuous yarn links integrally connecting said groups, a main seam transversely crossing the loop groups and longitudinally traversing the links to secure the loop groups and the links in permanent alignment, and completely removable side seams spaced from opposite sides of the links and on opposite sides of the main seam and forming a plurality of temporary connecting chains between each pair of loop groups free from contact with and on opposite sides of said links.

7. A ball or pompon-forming fringe compris-

ing a fringe body consisting of spaced yarn loop groups, sinuous yarn links integrally connecting the ends of adjacent loop groups, central longitudinal stitching crossing the loop groups and longitudinally traversing the sinuous links to hold the loop groups and the links in position, and a plurality of spaced substantially parallel inner and outer securing means spaced from opposite sides of the links and releasably connecting the loop groups and free from contact with 10 said links.

8. The method of ornamenting a marked pile fabric which comprises sewing a plurality of alternately connected yarn links and looped groups of yarn with center stitches and also sewing 15 spaced inner and outer stitches transversely across the bight portions of the loops to form a fringe, cutting the looped groups transversely between the inner and outer stitches and removing the outer stitches and cut-off bight portions of 20 the loops, superimposing the remaining fringe

upon the pile fabric and aligning the cut fringe groups and links to coincide with the fabric marks, stitching the fringe groups and links along the longitudinal center line of the fringe to the fabric along the marks to hide the links in the fabric pile, and finally removing the inner stitches from the cut groups and fluffing the released cut yarn groups to form decorative spaced yarn clusters on the fabric pile.
